REINFORCED-CONCRETE STRUCTURE

Heinrich Griesel, Berlin, Germany

Application January 22, 1938, Serial No. 186,418
In Germany January 23, 1937

13 Claims. (Cl. 72—65)

My invention relates to reinforced-concrete structures, and more particularly to structures for ceilings and roofs in which beams are combined with slabs.

As designed heretofore, such structures are made with I-section steel beams and abutment stones inserted between the webs of the beams and trough-shaped or arcuate slabs.

It is an object of my invention to provide an improved structure of this kind. To this end, I provide hollow beams of reinforced concrete instead of the aforesaid steel sections, and dispense with the abutment stones by making such beams with upwardly converging abutment faces, and inserting between their abutment faces slabs having corresponding faces at their sides. The slabs are provided with steel insertions projecting beyond their abutment faces, and connected above the beams.

By these means the structure is simplified and its bearing capacity is increased, as compared with the old steel-beam structure aforesaid.

In the accompanying drawings, beams and structures embodying my invention are illustrated more or less diagrammatically by way of example.

In the drawings

Fig. 1 is a cross-section of an inverted trough-shaped beam with transverse struts inserted at its lower end,

Fig. 2 is a cross-section of a similar beam cast integral with a cover plate at its lower side,

Fig. 3 is a partly sectional end elevation of a trough-shaped slab, and

Fig. 4 is a similar illustration of an arcuate slab,

Fig. 5 is a cross-section showing a panel of a ceiling equipped with trough-shaped, and

Fig. 6 is a similar section, partly in end elevation, of a panel equipped with arcuate slabs;

Fig. 7 is a cross-section of a beam forming part of the ceiling illustrated in Fig. 6, with means for supporting the ceiling plaster,

Fig. 8 is an end elevation of a beam of the same ceiling structure showing mortar grooves in the abutment faces of the beam and the arcuate slabs,

Fig. 9 is a section on the line IX—IX in Fig. 5,

Fig. 10 is a section on the line X—X in Fig. 7,

Fig. 11 is partly a cross-section, and partly an end elevation, and

Fig. 12 is a plan view, of a beam and two trough-shaped slabs, with interengaging spaced projections on the abutment faces of the beam and the slabs,

Fig. 13 is an end elevation showing steel members connecting the steel insertions of the beam with those of the adjacent trough-shaped slabs, and

Fig. 14 is a similar elevation showing the connection for arcuate slabs.

Referring now to the drawings, and first to Fig. 1, this inverted trough-shaped beam 1 is of trapezium section, with upwardly inclined converging abutment faces 4 at opposite sides. Steel transverse loops 7 are inserted in the concrete substance of the beam, and connected to longitudinal steel members 8 arranged in pairs at the top of the beam, and in its base flanges 30. 14 are plaster-supporting loops suspended from the members 8 and projecting from the lower faces of the flanges 30. 9 are transverse struts inserted in the lower side of the beam, and 7' are steel insertions in the struts which are connected to the longitudinal members 8 in the base flanges 20. 30. 19 is a groove in the upper face of the beam. Such grooves are arranged in spaced relation along the beam, for a purpose to be explained below.

Referring now to Fig. 2, this beam 1' is similar 25 to the one illustrated in Fig. 1 but has a cover plate at its lower side which is made integral with the body of the beam, and the loops 7 are continuous all round.

The beams are made trough-shaped, or with 30 a trapeze cross-section, in order to reduce their weight. The loops 7 and 7', and the longitudinal steel members 8, make up together a basket-like structure all round the cavity in the beams and provides for maximum bearing capacity to which 35 the base flanges 30 contribute.

In the structures which will now be described by way of example, the beam 1 illustrated in Fig. 1 is used but obviously the beam 1', Fig. 2, might be used as well. It is also understood that certain details described for a given kind of slabs 40 can also be arranged, with suitable modifications, for the other kind.

Referring now to Figs. 3, 5, and 9, trough-shaped ceiling slabs 2, preferably made with passages 16 for saving weight, are inserted between two beams 1,—or 1'—with their open sides up, and their upwardly divergent abutting faces 4 placed against the faces 4' of the beams. The bases of the slabs 2 are recessed at opposite 50 sides at the lower ends of their faces 4, for the reception of the flanges 30 on the beams. The slabs have steel insertions 5 which project from their abutment faces 4 at both sides, their projecting ends are placed in the corresponding 55

- groove 19 of the beam 1, tied together at 6, and covered with cement to protect them from rust. As will appear from Fig. 9, the ends of the slabs 2 are scarfed at 13, and preferably the receding 5 portion of the scarf is chamfered for the reception of a wedge-sectioned layer of mortar 15. By this means, tight joints are obtained. The insertions 5 at the ends of the slabs are preferably placed in the projecting ends of the scarves 10 13 so that they support not only their own, but also the adjacent slab. With light structures, such as country houses, a single insertion 5 at these points may be sufficient. 11 is plaster supported by the loops 14.
- 15 Referring now to Figs. 4, 6, 7, 8, and 10, arcuate slabs 3, with passages 16 and steel insertions 5 as described for the slabs 2, are abutted, concave side down, against the abutment faces 4' of two beams 1 with their own abutment faces 4. 20 If desired to obtain a tighter fitting joint, the abutment faces of both the beams and slabs, or only the beams, or only the slabs, are provided with mortar grooves 12, as shown in Fig. 8. The steel insertions 5 are connected at 6 in the 25 grooves 19, as described.
- 30 The joints at the ends of the arcuate slabs 3 might be made like those shown for the trough-shaped slabs 2 at 13, 15 in Fig. 9, or they are made as shown in Fig. 10, with grooves in the ends of the slabs making up together a semi-cylindrical space filled with mortar 13'. It is understood that the joint shown in Fig. 9 is not limited to trough-shaped, and the joint in Fig. 10 is not limited to 35 arcuate slabs.
- 35 In order to effect a positive connection between the slabs and beams, spaced recesses are formed in the abutment faces of the beams and slabs to form a sort of racks. An arrangement of this kind is illustrated for trough-shaped slabs 2 in Figs. 40 11 and 12, it being understood that it might as well be provided for arcuate slabs 3. The abutment faces of the beam 1 are provided with spaced recesses 17 which are entered by the non-recessed portions 18 of the slab abutment faces, as shown 45 in Fig. 12. This figure also shows the connections 6 between the steel insertions 5 of the slabs 2 which are placed in the grooves 19 of the beam, as described, and protected by a layer of cement in each groove.
- 50 50 By the rack-like means 17 and 18, as described, a positive connection between the beams and the slabs is provided which prevents any relative displacement of the beam and the slabs, and is strong against shifting and tension-exerting forces.
- 55 55 The interengagement of the beams and slabs is still more improved by not only connecting the steel insertions in the slabs to each other but by also connecting them to the steel in the beams.
- 60 Referring to Fig. 13, steel members 20 are embedded in the flanges 30 of the beam 1 and anchored on its longitudinal lower steel members 8. The members 20 extend upwardly through the joints between the slabs where they are bent about steel insertions 21 projecting into the joints, inserted in the corresponding groove 19, and connected at 6' in the manner described. The longitudinal steel insertions 21 are placed in longitudinal grooves of the slabs and the grooves are filled in with cement after the steel has been inserted.
- 65 70 Instead of longitudinal steel members cemented in the slabs in the manner described, short pins may be provided which extend across the joints receiving the connections 20.
- In addition to this, a second longitudinal member, or pin, 23 may be provided below the mem-
- ber, or pin, 21 in the slabs 2, and a second connecting member 22 be placed about the parts 21 and 23 in the joints. The ends of the members 22 are placed in the groove 19, and connected at 6''. The lower longitudinal steel members 8 in the 5 flanges 30 of the beams, and the members 20, 22 with the longitudinal members, or pins, 21 and 23 make up a basket-like structure at both sides of the beam 1, including the beam and the two slabs 2 abutted against it. This structure is very 10 strong but may be further braced by transverse members 24 connecting the steel insertions 5 of the two slabs 2 across the lower side of the beam 1 where a groove 19' is provided for their reception. The members 24 are inserted in the groove 19', 15 their ends are connected at 25, and the groove is filled with cement, as and for the purpose specified. The connection at 25 is so made that it imparts initial tension to the members 24 and the bearing capacity of the system of beams and slabs 20 is further, and considerably, increased thereby, and the system is equal to an integrally cast ceiling of reinforced concrete.
- Referring now to Fig. 14, where arcuate slabs 3 are provided, each slab has a pair of superimposed 25 longitudinal steel members 26 and 27, and the connecting members 20 are placed about both longitudinal members 26 and 27 in each slab, their ends being connected in the groove 19 at 6', and covered with cement, as described. This is also 30 a basket-like and very strong structure.
- The structures described with reference to Figs. 13 and 14 may also be combined with the rack-like connection illustrated in Figs. 11 and 12. Recesses 17 are shown in Fig. 14. 35
- Supporting the plaster 11 is easy with trough-shaped slabs, as will appear from Fig. 5, since the bottoms of the troughs present surfaces for the plaster to adhere to. With arcuate slabs, however, extra bars 10 must be arranged for this 40 purpose, as shown in Figs. 6, 7, 10, and 14. The bars are made of reinforced concrete and are placed on the flanges 30 with their stepped ends. They also support any cables, heating pipes, etc., which may be placed in the cavity below the 45 arcuate slabs 3.
- The beams 1 or 1', the slabs 2 or 3, and the mortar-supporting bars 10, are made on a quantity production basis and allowed to solidify thoroughly. They are then assembled in situ, with 50 an ample supply of mortar at the abutments and joints. In this manner, I obtain a fire-proof roofing or ceiling structure assembled in dry condition which is as strong against thrust and tension as a cast-concrete structure. 55
- I claim:
1. In a reinforced-concrete structure, hollow beams having upwardly converging abutment faces at both sides, steel insertions in the beams, slabs having abutment faces at their sides to fit the abutment faces of the beams, and steel insertions in the slabs projecting beyond their abutment faces and connected together above the beams. 60
  2. A reinforced-concrete structure as claimed in claim 1 wherein the upper faces of said hollow beams are provided with spaced grooves for accommodating said projecting steel insertions. 65
  3. In a reinforced-concrete structure, hollow beams having upwardly converging abutment faces at both sides, loops and longitudinal members of steel in the beams, making up together a basket-like structure, slabs having abutment faces at their sides to fit the abutment faces of the beams, and steel insertions in the slabs pro- 70 75

jecting beyond their abutment faces and connected together above the beams.

4. In a reinforced-concrete structure, hollow beams having upwardly converging abutment faces at both sides, slabs having abutment faces at their sides to fit the abutment faces of the beams, steel insertions in the slabs projecting beyond their abutment faces and connected together above the beams, flanges at the lower ends of the abutment faces of the beams, longitudinal steel members in the flanges, and steel loops in the body of the beams connected to the longitudinal members.

5. In a reinforced-concrete structure, hollow inverted trough-shaped beams having upwardly converging abutment faces at both sides, a transverse structure in the lower open side of the trough, steel insertions in the beams, and steel insertions in the cover plates connected to the insertions in the beams, slabs having abutment faces at their sides to fit the abutment faces of the beams, and steel insertions in the slabs projecting beyond their abutment faces and connected together above the beams.

25 6. In a reinforced-concrete structure, hollow beams having upwardly converging abutment faces at both sides, steel insertions in the beams, slabs having abutment faces at their sides to fit the abutment faces of the beams, steel insertions in the slabs projecting beyond their abutment faces and connected together above the beams, and plaster-supporting loops projecting from the lower sides of the beams.

7. In a reinforced-concrete structure, hollow beams having upwardly converging abutment faces at both sides, steel insertions in the beams including loops and lower longitudinal members, slabs having abutment faces at their sides to fit the abutment faces of the beams, steel members in the slabs arranged to cross the joints at the ends of the slabs, connecting members in the joints extending from the lower longitudinal members in the beams to the upper side of the beams in contact with the joint-crossing members, a connection for the free ends of the connecting members above the beam, and steel insertions in the slabs projecting beyond their abutment faces and also connected above the beams.

50 8. In a reinforced-concrete structure, hollow beams having upwardly converging abutment faces at both sides, steel insertions in the beams including loops and lower longitudinal members, slabs having abutment faces at their sides to fit the abutment faces of the beams, steel members in the slabs arranged to cross the joints at the ends of the slabs, connecting members in the joints extending from the lower longitudinal members in the beams to the upper side of the beams in contact with the joint-crossing members, a connection for the free ends of the con-

necting members above the beam, steel insertions in the slabs projecting beyond their abutment faces and also connected above the beams, and transverse members connecting the insertions in the slabs across the lower side of each beam.

9. In a reinforced-concrete structure, hollow beams having upwardly converging abutment faces at both sides, and spaced grooves in their upper and lower faces, steel insertions in the beams including loops and lower longitudinal members, slabs having abutment faces at their sides to fit the abutment faces of the beams, steel members in the slabs arranged to cross the joints at the ends of the slabs, connecting members in the joints extending from the lower longitudinal members in the beams to the upper side of the beams in contact with the joint-crossing members, a connection for the free ends of the members in the upper grooves of the beams, steel insertions in the slabs projecting beyond their abutment faces and also connected in the upper grooves of the beams, and transverse members connected to the insertions in the slabs with their inner ends, and connected to each other at their outer ends in the lower grooves of the beams.

10. In a reinforced-concrete structure, hollow beams having upwardly converging abutment faces at both sides, steel insertions in the beams, slabs having abutment faces at their sides to fit the abutment faces of the beams, steel insertions in the slabs projecting beyond their abutment faces and connected above the beams, and members connecting the insertions in the beams and in the slabs to make up a basket-like structure.

11. In a reinforced-concrete structure, hollow beams having upwardly converging abutment faces at both sides, steel insertions in the beams, slabs having abutment faces at their sides to fit the abutment faces of the beams, steel insertions in the slabs projecting beyond their abutment faces and connected together above the beams, and scarfed joints at the ends of the slabs.

12. In a reinforced-concrete structure, hollow trapezoidal beams having upwardly converging abutment faces at both sides, steel insertions in said beams, slabs having abutment faces at their sides adapted to cooperate with the abutment faces of said beams, laterally projecting flanges on the lower portion of said beams, said slabs having complementary recessed portions adapted to fit over said flanges, whereby said slabs are supported thereon, and steel insertions in said slabs projecting beyond their abutment faces and connected together above said beams.

13. A reinforced-concrete structure as claimed in claim 12 wherein said protecting steel insertions extend above and below said beams beyond their abutment faces and are connected together above and below said beams.

HEINRICH GRIESEL.
